TETHER TOY

Angel F. Hernandez, 1210 NE. 81st St. Terrace,
Miami, Fla. 33138

Filed Jan. 27, 1971, Ser. No. 110,363

Term of patent 14 years

Int. Cl. D21—01

U.S. Cl. D34—15

FIG. 1 is a side elevational view of a new design for a tether toy;

FIG. 2 is a cross sectional view of the upper portion of the toy taken along the lines 2—2 of FIG. 1;

FIG. 3 is a bottom plan view of the upper portion of the toy as seen in FIG. 1;

FIG. 4 is a top plan view of the lower portion of the toy as seen in FIG. 1.

I claim:

The ornamental design for a tether toy, as shown and described.
